UNITED STATES PATENT OFFICE.

GEORGE E. McMASTER, OF BELLINGHAM, WASHINGTON.

ADVERTISING DEVICE.

1,383,413.

Specification of Letters Patent.

Patented July 5, 1921.

Application filed February 28, 1921. Serial No. 448,699.

To all whom it may concern:

Be it known that I, GEORGE E. McMASTER, a citizen of the United States, residing at Bellingham, in the county of Whatcom and 5 State of Washington, have invented a new and useful Advertising Device, of which the following is a specification.

My invention relates to advertising devices having attention-drawing and attractive features other than the advertisements displayed, and the object of my invention is to use animated scenery as an attractive feature in connection with advertisements which may be either animated or still.

15 I attain this object with the mechanism illustrated in the four sheets of accompanying drawings in which Figure 1 is a front elevation of my device showing the advertising spaces and the first scene, Fig. 2 is a front elevation of my device with the cover removed, Fig. 3 is a plan view of Fig. 1, Fig. 4 is an end elevation of Fig. 3, Fig. 5 is a front elevation of a screen on which is shown a scene that is displayed instead of the removable part of said first scene shown in Fig. 1, Fig. 6 is a front elevation of a screen on which is shown a scene that is displayed instead of the removable part of the scene shown in Fig. 5, Fig. 7 is an elevation view 20 of a screen on which is shown the final scene which ultimately replaces the removable parts of the scenes shown in Figs. 1, 5 and 6, Fig. 8 is a front elevation of one of three similar iris diaphragms, and Fig. 9 is a plan view of Fig. 8 partly in section on the bent line 9—9. Both Figs. 8 and 9 are drawn on a larger scale.

Similar characters refer to similar parts throughout. Certain parts are broken away 40 to show other parts hidden thereby.

The device used herein to disclose my invention comprises a board on which are displayed advertisements and having a centrally located scenic stage automatically operable to open and close vistas of changing range which terminate in a scene of maximum attractiveness, and then to continue the cycle of automatic changes.

More particularly: 10 is the base of the 50 housing of my device. 11 is the back of said housing. 12 is a cover which, with said base and back, completes said housing. 13, 13 are screws for fastening said cover to the back and base. 14, 14 are spaces on the front of 55 cover 12 reserved for advertisements. 15 is a central space on said cover front reserved

for decorative designs. 15^a is a central opening in space 15. 16 is a screen fixed on diaphragm cover 21^a behind and adjacent to cover 12. 16^a is an opening in screen 16 in line with opening 15^a. 17 is a screen fastened to diaphragm cover 22^a and located behind screen 16. 17^a is an opening in screen 17 in line with openings 15^a and 16^a. 18 is a screen fastened to diaphragm cover 23^a and 60 located behind screen 17. 18^a is an opening in screen 18 in line with openings 15^a, 16^a, 17^a. 19 is a screen fastened to back 11 behind screen 18. 20, 20 are floor plates between screens 16 and 17, 17 and 18, and 18 and 19. 70 21 is an iris diaphragm having cover 21^a and fixed next behind and parallel with the front of cover 12. 22 is an iris diaphragm having cover 22^a and fixed next behind diaphragm 21 parallel and in line therewith. 23 is an 75 iris diaphragm fixed next behind, parallel and in line with diaphragm 22. 23^a is the cover of diaphragm 23. 24, see Figs. 8 and 9, is one of nine similar vanes of the iris of diaphragm 21. 25, 25 are studs in dia- 80 phragm 21 on which vanes 24 are pivotally mounted. 26, 26 are teeth, one only, on each of vanes 24 engaged with teeth in an external gear. 27 is an external gear revolvable through a short arc in the housing of dia- 85 phragm 21, each one of the teeth 28, 28 or which engages the tooth on one of vanes 24. 29 and 30 are stems fastened to gear 27 which protrude through an opening in the housing of 21, and are movable with gear 27 to their 90 dotted positions at 29' and 30', which movement causes vanes 24 to move to their dotted positions fully opening hole 32. 31 is a part- 95 ing ring mounted between the pivoted ends and the overlying ends of vanes 24 to prevent interferences between the same. 32 is a central hole through the housing of diaphragm 21 including the cover 21^a. In diaphragm 22 the cover is marked 22^a, the iris vanes 24^a, and the stems 29^a and 30^a respectively. In 100 diaphragm 23 the cover is marked 23^a, the iris vanes 24^b, and the stems 29^b and 30^b respectively. The central opening in dia- phragm 22 is marked 32^a, and the central opening in diaphragm 23 is marked 32^b. 105 33, 33, 33 are brackets fastened to back 11 and to each of diaphragms 21, 22 and 23. 34 is a gear wheel mounted for revolution on a bearing 35 which is fastened to back 11. 36 is a gear wheel having the same number 110 of teeth as gear 34, with which it is engaged, mounted for revolution in bearing 37 which

is fastened to back 11. 38 is an intermediate gear wheel engaged with gears 36 and 40 and mounted for revolution in bearing 39 which is fastened to back 11. 40 is a pinion gear engaged with gear 38 and mounted fixed on shaft 42. 41 is a bearing fixed to back 11. 42 is a shaft mounted for revolution in bearings 41 and 43 and has fixed thereon pinion 40 and worm wheel 44. 43 is a bearing fastened to base 10 and mounting shaft 42. 44 is a worm wheel mounted fixed on shaft 42. 45 is a worm engaged with worm wheel 44 and mounted fixed on motor shaft 46. 46 is the shaft of electric motor 48 and is mounted for revolution in said motor frame and in an outer bearing 47, which is fastened to base 10. 48 is an electric motor, the electric connections to which are not shown, mounted on base 10 and its extended shaft mounts fixed worm 45. 49 is an arm fastened to gear wheel 34 adapted to bear against stems 30, 30^a and 30^b, simultaneously during a part of each revolution of said gear. Stems 30, 30^a and 30^b stand one behind the other, as shown in Fig. 2, and are all moved from the position shown in dotted lines to the full-line position by arm 49. 50 is an arm fastened to gear wheel 36 adapted to move stem 29 only from its full-line to its dotted-line position once during a small part of each revolution of said gear. 51 is an arm fastened to wheel 36 adapted to move stem 29^a only from its full-line to its dotted-line position during a small part of each revolution of wheel 36. 52 is an arm fastened to wheel 36 adapted to move stem 29^b only from its full-line to its dotted-line position once during a small part of each revolution of said wheel 36. Thus arm 49 in its movement in revolution with gear wheel 34 bears against all of stems 30, 30^a and 30^b at the same time and simultaneously covers each of holes 32, 32^a and 32^b by causing all of the iris vanes in the three diaphragms 21, 22 and 23 to move in front of said holes. Then when arm 50 bears on and moves stem 29 hole 32 is uncovered and the scene on screen 17 comes into view; after a period of pause arm 51 bears on and moves stem 29^a and hole 32^a is uncovered exposing the scene on screen 18; and finally after a pause arm 52 bears against and moves stem 29^b uncovering hole 32^b when the final scene, that on screen 19, is exposed to view, and remains exposed till arm 49 again comes in contact with all of stems 30, 30^a and 30^b at once and again closes each of the irises and covers each of said holes.

Preferably, arms 49, 50, 51 and 52 are so located on said gear wheels that the period of pause between the opening of diaphragms 21 and 22 is equal to that between the opening of diaphragms 22 and 23, but the time between the opening of diaphragm 23 and the closing of all the diaphragms is greater than those equal periods of pause.

53 is a pulley fixed to intermediate gear 38. 54 is a belt from pulley 53 to pulley 55. Pulley 55 is mounted for revolution in bearing 60. 56 is a pulley fixed to pulley 55. 57 is a belt from pulley 56 to pulley 58. Pulley 70 58 is mounted for revolution in bearing 61 fastened to back 11. 59, 59 are a number of objects shaped like men, women, children, and lower animals fastened to belt 57 and protrude through a slot in floor 20, see Fig. 75 4, as the upper part of said belt passes closely beneath said floor. These figures move across the background and disappear behind the buildings shown at the right of the stage. 60 is a bearing mounting pulley 56 and is fastened to back 11. 61 is a bearing mounting pulley 58 and is fastened to back 11.

The scene depicted on each iris is completed on the screen fastened to the diaphragm in which the iris operates, and the scene disclosed as each iris is successively opened is intended to differ from yet blend with the scene partly removed by the opening of said iris. But by preference, the scene on the rear screen 19 is more pleasing than the others and may show, in addition to the moving figures illustrated, moving birds, vehicles, illuminated fountains and similar attractive features.

Having thus fully disclosed my invention, what I claim is new and desire to secure by Letters Patent is,—

1. In an advertising device in combination, an advertisement-display board having advertisements displayed thereon, a scenic stage located on said display board, a plurality of stationary, scenery flies set on said stage having artistic designs thereon, a plurality of protractile and withdrawable scenery carriers on said stage having artistic designs thereon which blend with the designs on said stationary flies, and means to automatically protract and withdraw said scenery carriers into and out of view at recurrent intervals with intervening periods of pause.

2. In an advertising device in combination, an advertising-display board having advertisements thereon; a scenic stage located on said display board; a plurality of stationary screens on said stage each having an artistic design thereon and a vista opening therein; a plurality of iris diaphragms, one adjacent to and behind each of said stationary screens, the iris of which is retractile and protractile and has depicted thereon an artistic design visible through said vista opening in said screen when said iris is protracted, said design thereon blending with the design on said screen; automatic means to retract each of the irises of said diaphragms in sequence, beginning with the outermost, at spaced intervals of time with an intervening period of pause; and automatic means to protract said irises.

3. In an advertising device in combination, an advertising-display board having advertisements thereon; a scenic stage located on said board; a plurality of stationary screens on said stage each having an artistic design depicted thereon and a vista opening therein; a plurality of iris diaphragms, one adjacent to and behind each of said screens, the iris of which is retractile and protractile and has depicted thereon an artistic design visible through said vista opening in said screen when said iris is protracted, said design blending with the design on said screen; means to automatically retract each of said irises in sequence, beginning with the outermost, at spaced intervals of time with an intervening period of pause; means to automatically protract said irises; and a stationary screen 20 at the rear of said stage having an artistic design thereon.
4. In an advertising device in combination, an advertising-display board having advertisements thereon; a scenic stage located on said board; a plurality of stationary screens on said stage each having an artistic design depicted thereon and a vista opening therein; a plurality of iris diaphragms, one adjacent to and behind each of said screens, the iris of which is retractile and protractile and has depicted thereon an artistic design visible through said vista opening in said screen when said iris is protracted, said design blending with the design on said screen; means to automatically retract each of said irises in sequence, beginning with the outermost, at spaced intervals of time with an intervening period of pause; means to automatically protract said irises; a stationary screen at the rear of said stage, behind said iris diaphragms, having an artistic design thereon; figures of living objects movable in front of said rear screen and behind the rear diaphragm; and automatically operative means to move said figures. 25 30 35 40 45

GEORGE E. McMaster.
